ATTORNEY

UNITED STATES PATENT OFFICE.

WILLIAM S. HADAWAY, JR., OF NEW ROCHELLE, NEW YORK.

KINETIC HEAT INSULATION.

Original application filed July 26, 1917, Serial No. 182,815. Divided and this application filed August 18, 1921. Serial No. 493,486.

To all whom it may concern:

Be it known that I, WILLIAM S. HADAWAY, Jr., a citizen of the United States of America, and a resident of New Rochelle, Westchester County, and State of New York, have invented certain new and useful Improvements in Kinetic Heat Insulations, of which the following is a specification.

This invention relates to kinetic heat insulation and more particularly to heaters wherein vapor is employed as a working medium.

Broadly stated it is the object of the present invention to provide improved means for transferring a vapor into a heat chamber in successive stages, and employing the vapor as a kinetic insulating medium in the several steps. Thus an efficient form of heat insulator is provided, which may be compared to an electric conductor upon which a counter electro-motive force is impressed. In other words, I provide a mass surrounding the high temperature body or chamber and cause an inward flow of a heat carrier through the mass which directly opposes the outward heat flow which the ordinary heat losses tend to produce.

By this means I fix the temperature throughout the insulating mass, maintaining the outside walls at the temperature of the surrounding medium and gradually increasing the temperature through the mass to the temperature of the interior.

More particularly it is an object of my invention to provide a heat chamber and an insulating body therefor including a passageway for incoming medium, whereby the medium may be supplied to the passage and there be prepared for use, so that when delivered to the heat chamber it is in suitable condition for use.

Another object relates to means for retaining the medium in a definite stage or position relative to the heat chamber, whereby the medium forms a wall or layer for insulating the chamber.

Another object relates to the provision of a plurality of such layers, arranged in successive stages, whereby the temperatures thereof increases in steps as the chamber is approached.

Another feature relates to the provision of metallic walled-spacers, whereby the construction of the insulating body is rendered

rigid, serving also to form heat transferring medium retaining means.

Still another feature relates to the provision of a granular filler between at least some of the spacers, whereby the flow of medium may be retarded in a predetermined degree.

Another object relates to a plurality of layers or spacers surrounding a relatively high temperature body whose spacing varies either regularly or otherwise whereby more space or volume is provided for the hotter and expanded vapor.

Another object relates to a plurality of layers or spacers whose thickness varies either regularly or otherwise whereby the surface or area of the spacer contacted by the vapor varies in amount as the vapor circulates.

Another object relates to a simple, light and inexpensive heat insulation for a high temperature body, wherein the high temperature body is enveloped in a plurality of spaced receptacles which serve to retard the flow of heat by enclosing air or other gases or vapors between their surfaces and which also serve as a tortuous path for a vapor or gas which is heated as it circulates and thereby cools the surfaces.

Other objects will appear as the description of the invention progresses.

This application is a division of my co-pending application Serial No. 182,815 filed July 26, 1917, heaters and heat insulation.

Referring to the drawings:

Figure 1 shows a horizontal section of a heat chamber having insulating walls, embodying the present invention; and

Figure 2 shows a sectional elevation thereof.

Like reference characters denote like parts in the several figures.

The drawings show one embodiment of my invention which comprises a heat chamber 10 constituting a furnace or oven or other high temperature chamber. The walls and floor 100 of the furnace are formed of a plurality of layers 11 of insulating material which are spaced apart by spacers, 12, 13, 14.

Each spacer comprises a pair of walls 15, of sheet metal or other suitable material between each pair of which may be a granular refractory material 16 such as granular carborundum or the like supported between

and forming a passage within the walls.

The insulating layers 11 may be alike or may preferably be selected because of special fitness for the temperatures at which the 5 respective layers are maintained when the furnace is in operation.

The outer wall 20 may be of any suitable construction such as refractory material or the like. The walls and floor of the chamber 10 may be of any desired material, according to the work to which the heat is to be applied. For example it also may be of refractory material or the like.

The heat insulation of the outside walls 15 of the vapor jacket may be of well known forms such as 85% magnesia for example or may be omitted altogether.

A cover 30 is provided for the heat chamber, and in the present embodiment is formed 20 to correspond with the upper portion of the furnace.

The outer passage 14 is provided with a vapor supply pipe 31 disposed at one side as shown in Figure 2, leading from a suitable 25 source of vapor 32 such as a steam boiler or the like. A connection 33 extends between passages 14 and 13 and the opposite side of the furnace.

Similarly the passage 13 is connected with 30 the inner passage 12 and the latter in turn with the interior of the heat chamber 10.

The heat chamber may take the form of a furnace arranged to employ vapor as a combustion agent, such as shown in my copending application Serial No. 389,545 filed June 35 17, 1920, for electric furnaces or it may employ vapor as a heating element, such as a steam chamber.

The cover 30 may be porous or may be 40 provided with an outlet 35 leading from the chamber 10 to discharge the vapor therefrom when desired.

The passages may be interconnected by two or more pipes or connecting passages 45 and the arrangement is such that the hot vapor such as steam supplied through the pipe 31 fills the outer steam space or passage 14 and flows slowly therethrough and then through the pipe 33 to the next passage.

As the vapor enters each successive passage its temperature is increased, corresponding to the passage, which in turn varies according to the distance of each particular passage from the furnace chamber 55 10 within.

Finally, the steam as it enters the chamber is substantially at the temperature of the chamber itself.

60 Thus it will be seen that the temperature of the spacers 12, 13, 14 between the layers of insulation is limited by the rate at which the outward flow of heat is absorbed by the inwardly flowing vapor.

65 By selecting the granular material used in

the spacers 12, 13, 14, the degree of resistance to the passage of the vapor may be predetermined to accord with the relative temperatures of the layers. Furthermore, the material used in the several spacers may be 70 unlike, thus providing unlike degrees of resistance in the successive passages and retarding the flow of vapors in different degrees.

The present embodiment is only one of a 75 variety of forms in which the invention may be practised, and numerous changes in proportion, arrangement and number of parts may be made without departing from its spirit; therefore, it is expressly understood 80 that the scope of the invention is not limited by the particular form disclosed, reference being had to the appended claims for that purpose.

What is claimed is:

1. A heat insulation comprising a plurality of spaced layers of unlike materials, each adapted to the temperature to which it is subjected, spacers between adjacent layers, each spacer comprising a pair of spaced metallic walls and a mass of granular refractory material positioned between said walls, passages connecting adjacent spacers in successive order, and means for supplying steam to a predetermined one of said spacers.

2. A heat insulation comprising a plurality of spaced layers of unlike materials, each adapted to the temperature to which it is subjected, spacers between adjacent layers, 100 each spacer comprising a pair of spaced metallic walls and a mass of granular carbondum positioned between said walls, passages connecting adjacent spacers in successive order, said passages being positioned alternately at opposite sides of the insulation.

3. A heat insulation for a heat chamber comprising a plurality of spaced layers of unlike materials each adapted to the temperature to which it is subjected, spacers between adjacent layers, each spacer comprising a pair of spaced metallic walls and a mass of granular refractory material positioned between said walls, passages connecting adjacent spacers in successive order, 110 means for supplying steam to the outwardly disposed one of said spacers, and a passage between the inwardly disposed one of said spacers and the heat chamber.

4. A heat insulation comprising a plurality of layers, spacers between the layers and means for supplying fluid to fix the temperatures of said spacers.

5. A heat insulation comprising a plurality of layers, spacers between the layers and means for supplying fluid to said spacers in consecutive order to fix the temperatures thereof in progressively changing degree.

6. A heat insulation comprising a plural-

- ity of spaced layers of unlike materials, each adapted to the temperature to which it is subjected, and spacers between adjacent layers, each spacer comprising a pair of spaced 5
5 metallic walls and a porous mass positioned between said walls.
7. A heat insulation comprising a plurality of spaced layers of unlike materials, each adapted to the temperature to which it is subjected, and forming a fluid passage, and means for supplying fluid to said passage 10
10 for fixing the temperature of each layer.
8. A heat insulation comprising a plurality of spaced layers of unlike materials, each adapted to the temperature to which it is subjected, and forming a fluid passage, and means for supplying fluid to said passages in successive order for fixing the temperature of each layer, whereby the temperature 15
15 of the layers are successively increased towards the direction of flow of fluid.
9. A heat insulation comprising a plurality of spaced layers of unlike materials, each adapted to the temperature to which it is subjected, and means for supplying steam 20
20 to the spaces consecutively.
10. A heat insulation comprising a plurality of spaced layers of unlike materials, each adapted to the temperature to which it is subjected, and means for supplying steam to the spaces in succession from the outer 25
25 space inward.
11. A heat insulation comprising a plurality of layers, and spacers between each pair 30
30 of layers, said spacers comprising a pair of spaced walls.
12. A heat insulation comprising a plurality of layers, and spacers between each pair of layers, said spacers comprising a pair of spaced metallic walls and a porous mass positioned between said walls. 35
35
13. A heat insulation comprising a plurality of layers, and spacers between each pair of layers, said spacers comprising a pair of spaced metallic walls and a porous mass of granular refractory material positioned between said walls and forming a fluid passage. 40
40
14. A heat insulation for a heat chamber comprising a plurality of spaced layers of unlike materials each adapted to the temperature to which it is subjected, and means for supplying steam to the spaces in succession from the outer space inward. 45
45
15. A heat insulation for a heat chamber comprising a plurality of spaced layers of unlike materials each adapted to the temperature to which it is subjected, and means for discharging the steam from the inner space. 50
50
16. A heat insulation for a heat chamber comprising a plurality of spaced layers of unlike materials each adapted to the temperature to which it is subjected, and means connecting with the heat chamber for discharging the steam from the inner space to the heat chamber. 55
55
17. A heat insulator for a heat chamber comprising a body of unlike materials separated by metallic walls, one of said materials being adapted to conduct a heat transferring medium through said insulator. 60
60
18. A heat insulator for a heat chamber comprising a body of unlike materials separated by metallic walls, one of said materials being adapted to conduct a heat transferring medium and means for supplying medium thereto through said insulator. 65
65
19. A heat insulator comprising materials of unlike porosity separated by metallic walls, and means for supplying to the more porous of said materials a heat transferring medium. 70
70
20. A heat insulation comprising a plurality of spaced layers of unlike materials, each adapted to the temperature to which it is subjected, and spacers between adjacent layers each spacer comprising a porous mass between at least one pair of said walls being of unlike characteristic relative to the mass between other pairs of walls. 75
75
21. A heat insulation comprising a plurality of layers, spacers between the layers and means for supplying fluid to fix the temperature of the spacers between the layers. 80
80
22. A heat insulation comprising a plurality of spaced layers of unlike materials, each adapted to the temperature to which it is subjected, and means for fixing the temperature of each layer. 85
85
23. A heat insulation comprising a plurality of spaced layers of unlike material, each adapted to the temperature to which it is subjected, and means for supplying fluid to fix the temperature of each layer. 90
90

In witness whereof, I have hereunto set my hand this 16th day of August, 1921.

WILLIAM S. HADAWAY, JR.
